United States Patent Office

Des. 184,156
Patented Dec. 23, 1958

184,156

FOOD SLICING MACHINE

Henry J. Talge, Kansas City, Mo., assignor to John C. Hockery, Kansas City, Mo., trustee for Henry J. Talge and Foster L. Talge

Application March 7, 1957, Serial No. 45,142

Term of patent 14 years

(Cl. D55—1)

Fig. 1.

Fig. 2.

Fig. 3.

Fig. 4.

Fig. 5.

Fig. 6.

Fig. 1 is a perspective view of a food slicing machine embodying my new design;

Fig. 2 is a perspective view showing the opposite side and end of same;

Fig. 3 is a plan view thereof;

Fig. 4 is a side elevational view thereof;

Fig. 5 is an end elevational view thereof; and

Fig. 6 is an elevational view thereof taken from the opposite end of Fig. 5.

The dominant features of the design reside in those portions illustrated in full lines.

I claim:

The ornamental design for a food slicing machine, as shown and described.
